US00D459132S

(12) **United States Design Patent**
Shea

(10) Patent No.: **US D459,132 S**
(45) Date of Patent: ** Jun. 25, 2002

(54) **SWING STRIP DISPLAY**

2,935,210 A 5/1960 Cohen

(76) Inventor: **Thomas M. Shea**, 1343 Rochester Rd.,
Suite 100, Troy, MI (US) 48083

(**) Term: **14 Years**

(21) Appl. No.: **29/128,427**

(22) Filed: **Aug. 24, 2000**

(List continued on next page.)

Primary Examiner—Brian N. Vinson

(74) Attorney, Agent, or Firm—Gifford, Krass, Groh,
Sprinkle, Anderson & Citkowski, P.C.

(57) **CLAIM**

I claim the ornamental design for a swing strip display, as
shown and described.

DESCRIPTION

(63) Continuation-in-part of application No. 09/280,285, filed on
Mar. 29, 1999, now Pat. No. 6,202,866, which is a continuation-
in-part of application No. 09/225,671, filed on Jan. 5,
1999, now Pat. No. 6,070,747, and a continuation-in-part of
application No. 08/888,558, filed on Jul. 7, 1997, now Pat.
No. 5,957,422.

FIG. 1 is a top, front, and left side perspective view of a
swing strip display showing my new design;

FIG. 2 is a left side elevational view of the vertical com-
ponent thereof;

FIG. 3 is a front elevational view of the vertical component
thereof;

FIG. 4 is a right side elevational view of the vertical com-
ponent thereof;

FIG. 5 is a rear elevational view of the vertical component
thereof;

FIG. 6 is a bottom plan view of the vertical component
thereof; and,

FIG. 7 is a top plan view of the vertical component thereof.
The horizontal component has been omitted from most
views for convenience of illustration.
